UNITED STATES PATENT OFFICE.

EDWIN J. BEST, OF WOODWARD, ALABAMA.

AUTOMATIC REVOLVING DUMP.

1,424,871.

Specification of Letters Patent. Patented Aug. 8, 1922.

Application filed July 14, 1919. Serial No. 310,810.

To all whom it may concern:

Be it known that I, EDWIN J. BEST, a citizen of the United States of America, residing at Woodward, in the county of Jefferson and State of Alabama, have invented 5 a certain new and useful Improvements in an Automatic Revolving Dump, of which the following is a specification.

My invention relates to an automatic revolving dump or side tipple adapted to receive cars singly or in multiple and dump them with a complete revolution or, if desired, with a partial revolution and an automatic return to initial position.

15 The rotary dumps now in use are revolved by a variety of mechanical appliances, all of which are more or less complicated especially in order to obtain a shockless stopping of the dump after each rotary movement. In 20 some instances the track for the mine car has been set off center in the dump to unbalance it for the purpose of starting the rotation of the dump by gravity, but inasmuch as the car becomes dumped during the 25 rotation, thus materially modifying the load in the dump, it has not been considered practical heretofore to rely upon the momentum attained by such dump to automatically right itself after a complete or partial rotation.

30 I have conceived that the power operating mechanism for dumps of this general class can be dispensed with and their automatic operation attained by utilizing the fly-wheel principle to store up sufficient energy during 35 the initial movement of the loaded dump, when it is heavily unbalanced, to supply the needed momentum or energy to restore the unloaded dump with ample margin of safety to its initial position. The fly-wheels 40 in opposing their inertia to the starting movement of the dump retard it and slow up its initial momentum, causing it to dump the contained material with less breakage and to operate with less stresses. Suitable 45 braking and stopping means are provided to stop the dump as it rights itself and to hold it during the transfer of the mine cars.

While it is to be understood that the fly-wheels for storing up the requisite energy 50 during the movement of the dump with the load therein may be of any suitable shape and type and may be located at various places on, under or connected to the dump, my preferred arrangement is to add the necessary weight to the dump supporting trun-

nion wheels so that these are converted into driving wheels to right the dump after its dumping operation.

My invention also comprises novel features in the method and mechanism for accomplishing the shockless stoppage of the dump, such mechanism being particularly designed for joint use with a pair of dumps arranged side by side and adapted to revolve in reverse directions.

My invention also comprises other novel details of construction and arrangements of parts which are hereinafter more fully described and pointed out in the accompanying claims, and which in their preferred embodiments only are illustrated in the accompanying drawings which form a part of this specification, and in which:—

Fig. 1 is a plan view of a pair of rotary dump cages which are each adapted for the simultaneous dumping of five cars arranged in multiple therein.

Fig. 2 is a view taken on the line 2—2 of Fig. 1, showing one of the dumping cages in side elevation.

Fig. 3 is an enlarged view taken on the line 3—3 of Fig. 1 with the car in the dump and the platform shown in cross section.

Fig. 4 is an enlarged cross sectional view through one of the dumping cages.

Fig. 5 is a vertical sectional view taken on the line 5—5 of Fig. 4 and showing one of the rolled steel tires or rails forming part of the dump cage.

Fig. 6 is an enlarged detail view of one of the trunnion wheels with the fly-wheel attachments.

Fig. 7 is a view of the stoppage means comprising a pair of pawls adapted to engage stop lugs rigidly connected to the tire rail.

Fig. 8 is a detail view taken on the line 8—8 of Fig. 3 and showing the brake mechanism co-acting with the stop lugs and the yielding arrangement for absorbing the shocks of stoppage.

Fig. 9 is a detail sectional view on the spring brake clamps taken on the line 9—9 of Fig. 8.

Similar reference numerals refer to similar parts throughout the drawings.

In the preferred embodiment of my invention illustrated, the two dump cages shown are duplicates and one only need therefore be described. This tipple or dump

is constructed of metal and comprises a number of rolled steel tires 1 which are made up of rails which after being bent are turned true to a perfect circle and serve the double purpose of frame and rolling device. The rails are therefore arranged with their heads or treads facing outwardly and their base flanges facing inwardly. These tire rails are further connected with rails 2 extending horizontally lengthwise through the dump cage and having their base flanges riveted to the bases of the tire rails. The rails 2 thus form the connecting ribs of the main body or skeleton frame of the dump cage and these ribs are again laced with angles 3 (see Fig. 2) extending from tire to tire and forming a construction similar in principle to the lattice girder. The cage is preferably made light on account of the automatic gravity dumping features hereinafter described, but the structural material employed is of sufficient strength to stand, without substantial depreciation, the dumping service under the most severe operating conditions.

25 The treads of the rolled steel tires 1 ride on trunnion wheels 4 and 4^a (see Fig. 6), the frame being fitted with short shafts 5 that turn in roller bearings 6 placed at each side of the trunnion wheels in a pair of bearing castings 7, the bases of which are mounted on and attached to the transverse supporting beams 8 of the tipple structure. These bearing castings 7 are substantially triangular in side elevation (see Fig. 4), and their top 30 portions are also suitably bolted to the tipple framework. The fly-wheels 9 are suitably connected by keys 10 to the overhung ends of each shaft 5 and the size and weight of these fly-wheels are arrived at by calculating 35 the fly-wheel load for the required speed, say average of 10 R. P. M., of the dumping cage and the loads of the cars to be handled thereing, and from this subtract the fly-wheel effect of the dump. In connection with the 40 operation of the dump I shall state the factors which control in the design of these wheels.

In addition to the tie rails 2 I provide a pair of track rails 11 which extend through 45 each dump cage, these rails being so placed that they form a run way for the cars to be handled in their respective dump. The rails are supported by transverse structural beams 12 which at their ends are riveted to plates 13 provided with curved marginal angles 14 which are riveted to the tire rails 1. These angles subtend a substantial arc of the tire rail so as to give the requisite load supporting strength and in addition thereto the beam 50 is suitably braced at its center by the angles 15 which are connected to plates 16 riveted to the tire rail. Each track rail 11 rests on the end 17 of a heavy metal bar 18, which end is bolted to the beam 12. The bars, beginning at points far enough from the rails

to clear the cars, are bent vertically and have their upper ends 19 bent horizontally outwardly and bolted to the top of the plates 13. A rail 20 is attached near the top of the vertical portion of each of these bars and overhangs inwardly so as to project over the wheels or wheel hubs of the cars standing on the track rails 11 of the dump, as seen in Fig. 3. These latter rails 20 therefore serve to support the cars in their inverted position.

My object in mounting the rails 11 and 20 at each side of the track on the same bent bar 18 is to preserve their relative adjustment while adapting them to be adjusted 70 relatively to the center of the cage both vertically and laterally, the lateral adjustment being made by changing the point of attachment of the ends 17 and 19 of the bar to the beam 12 and plate 13 and the vertical adjustment being obtained by the insertion of liners under the ends of the bar.

As illustrated, the rotary tippler is arranged so that the horizontal track for the cars comes in line with the tipple floor 21 but is off center in the cage, the tracks in the left hand tippler, Fig. 3, being preferably offset to the right and the tracks in the right hand tippler being offset to the left. In order that the tipplers, which are thus 90 unbalanced, may be held in position for receiving and discharging the mine cars 22, I attach to the web of one or all of the tire rails 1 on opposite sides thereof a pair of stops 23. These are more clearly illustrated in Fig. 7 where it will be seen that they have elongated bodies for the reception of a number of rivets and have at their forward ends enlarged heads 24, the outer side edges of which project laterally on each 95 side beyond the tread of the tire rail 1 and flush with the side edges of the base 25 of the rail 1 so that their forward ends will be engaged by the stop jaws 26 of a bifurcated pawl 27 which straddles the tread of 100 the tire rail 1 and has its ends struck on a curve from its bearing center. The forward ends of the stop heads 24 are similarly curved. These pawls are provided with bottom extensions 28 which straddle a bearing 29 in which a shaft 30 turns, on which shaft the bottom extensions 28 are keyed. The shaft 30 for long dumps is in sections 105 connected by suitable couplings 31 so as to extend the full length of the cage in order that pawls can be provided for each tire rail and all can be shifted together into and out of operating position by means of a crank arm 32 extending laterally under and beyond a dump cage and provided with an 110 operating handle 33 which passes upwardly through the tipple floor at a point convenient for the operator controlling the dumps. These pawls, due to their curved ends and the great leverage obtained by reason of the 115

length of their operating lever 32, can be readily disengaged from the stop lugs 24 so as to release the cages for the dumping operation.

- 5 The main supporting transverse beams 8 of the tipple are braced at their centers by trusses 34 and along on the centers of these beams rest other longitudinal beams 35 which support overhead a series of spaced 10 short transverse beams 36 which are suitably tied together and form a strong base upon which I mount a spring support for the stoppage mechanism, which spring support is built up of alternate tiers of longitudinal and transverse boards 37 and 38, respectively, (see Fig. 8) which are suitably connected to their supports. The bearing brackets 29 for the stop pawls are all mounted on these spring supports and between 15 each adjacent pair of stop bearings 29 I mount a vertical standard 40 which is provided on opposite sides with outwardly and downwardly inclined seats 42. The lower ends of the four pairs of angle bars 25 44 and 45 forming the brake or stoppage mechanism rest on the seats 42 and are adapted to transmit their thrust stresses through the standards 40 to their yielding timber supports. This stoppage means, one 30 of which is preferably provided for the opposite tire rails of the two dumps, comprises two pairs of angle irons 44 and 45 with curved braking flanges which conform to the curve of their respective tire rail tread 35 46 of the two angles are disposed on opposite sides of the treads of their respective tire rails, see Fig. 9, and are adapted to receive between them and to frictionally engage the outer side edges of the heads 24 of their respective stop lugs when the latter 40 move into position between them. At their upper ends the angles 44 and 45 are bent slightly apart (see Fig. 8) and are suitably attached to an overhead angle plate 43 bolted to the beam 47 which is suitably supported 45 at its ends by the uprights 48. The attachment is such that the units 44 and 45 of each pair can have their flanges 46 drawn together by the mechanism which will now be described so as to apply the requisite 50 friction to the stop lugs and thereby to brake the dump cages so as to reduce to a minimum the stoppage jar when the stop lugs engage the pawls 27.

As illustrated, I utilize two fastenings for 55 each set of braking units 44 and 45 for the two dump cages. These mechanisms comprise a screw bolt 49 which passes lengthwise of the dump between the adjacent tire rails 1 and between the axially disposed 60 flanges of the angle irons 44 and 45, as will

be seen more clearly in Fig. 9. A washer 50 and a nut 51 on the other end of the bolt will serve to engage the angle irons 45 of the lower fastening while a washer 52, loose on the bolt, will be pressed against the angles 70 44 by a coil spring 53 which is interposed between the washer 52 and a washer 54 held by a nut 56 mounted on the outer end of the bolt. The flanges of the angles 44 and 45 are notched at 56^a to form seats for the 75 washers 50 and 52. For the upper fastening, the construction is the same except the space between the angles being greater, plates 57 are substituted for the washers 50 and 52. The springs act to permit the opposite pair of brake angles 44, 45 to yield apart as the stop lugs 24 pass between them and their tension is adjusted to engage the stops with the desired friction to nearly bring the dump to rest. The angles carry inturned 80 stop lugs 39 which are disposed above the upper fastening and limit the approach of the angles when not in the act of braking the dump. In like manner the lower ends of the angles carry stops 41, which engage 90 the column 40, see Fig. 8, and limit the approach of the lower ends of the angles.

In order to take the end thrust from the dump cages and particularly when the latter are disposed at a slight incline, I provide end thrust trunnion rollers 58 which are mounted to turn in vertical bearings 59 and which engage the side faces of the lower tire ring 1. To avoid danger to the dump structure from the cars I provide the several 100 tire rails with outwardly flaring deflector plates 60 in radial alignment with the nearest corner of the cars. These would deflect the car past the tire rails and prevent serious damage to the cage. 105

In operation, after the car or cars have been delivered to the dump, the pawls 27 are released by raising the handle 33 and the weight of the car or cars and the material therein is heavy enough to cause by gravity 110 automatically the immediate rotation of the dump. The pawls being counterweighted by the lever arm 33 immediately right themselves as soon as released and stand in position to prevent the dump from returning past its initial position. The fly-wheels which are distributed along the dump cage on the same shaft, being thus distributed to eliminate shaft torsional deflection, will, on account of inertia and weight, first act to 115 retard the downward movement of the load. As the dump moves and starts the fly-wheels in motion they act to store up power or energy which they give out to drive the cage after its gravitating action ceases until it reaches its normal or initial position. The number of fly-wheels would be, in a sense, proportionate to the length of the dump and the number of cars to be handled thereby at 120 a time, it being preferable to distribute the 125 130

fly-wheel weight so as to avoid abnormal shaft torsional deflection. My object being to make use of the counterweight principle so that it will initially retard the unbalanced dump on its downward movement and will give the power back to the cage for righting itself, it should be understood that this counterweight may be distributed in various manners and at various points on or 10 connected to the cage but should always be designed and located so as to operate with the least co-efficient of friction and strain on the dump cage. As the dump cages in the arrangement shown complete their rotation the stop lugs pass between the braking mechanism and the dump is gradually slowed up until it is brought to a complete rest by the stop pawls 27 which are adapted to take the stopping shock without damage 15 by being mounted on the yielding board supports. The track rails 11 in the cages can be adjusted sidewise or vertically so as to vary the center of gravity of the loaded dump until the accumulated momentum derived therefrom works out satisfactorily with the fly-wheel mechanism.

The center of gravity of this automatic tippler, cars and load is above the center of rotation, and is sufficiently off center to set 20 the tippler in motion and to continue it in motion until the load is emptied and the tippler has righted itself; it is not designed so that the cars when empty can start the tippler on any downward movement, as the 25 center of gravity of the tipple with empty cars in righted position therein is below the center of rotation so that the dump would only tend to rotate responsive to the lateral offset of the car and tracks therein which 30 would not develop sufficient momentum for operating purposes. The detailed description of operation has, so far, concerned it self with dumps designed to rotate, i. e., after the load falls, the fly-wheel weight 35 wherever distributed, will carry the dump over 360° . But it should be understood that smaller fly-wheels can also be made to retard the speed so that the dump can rotate say approximately 200° , in which position 40 the center of gravity of the cars is at the opposite side from the original position with the cars loaded, which tends to revolve the dump in the opposite direction. This 45 force overcomes the initial momentum of the lighter fly-wheels, which is very slight and reverses their direction of rotation so that they will again right the dump as it swings back in the opposite direction, the small amount of power needed for this end 50 coming out of the energy stored in the fly-wheels as the dump starts to swing back after reaching its 200° angle.

While I have referred to the arrangement of the fly-wheel weight so as to retard 55 the gravitating movement of the dump as

my preferred arrangement, I nevertheless contemplate the use of the added fly-wheel weight on the dump when such retarding action will not be so effective as in a driven element.

This invention is not intended to be restricted in scope to the specific embodiments shown, but contemplates such modifications as come within the spirit and scope of the claims.

Having thus described my invention, what I claim as new and desire to secure by Letters Patent, is:—

1. An automatic rotary dump comprising a rotatable cage, means to unbalance the cage, releasable latch means to hold the dump against rotation when thus unbalanced, and fly-wheel means supported independently of and rotatable with the cage, said fly-wheel means being adapted by its inertia to retard the starting movement of the cage and to store up sufficient energy from an automatic gravitating movement of the unbalanced cage to positively return it to initial position.

2. An automatic rotary dump comprising a gravity operated self dumping rotary cage, and a fly-wheel movable with the dump and designed to positively right the cage by the expenditure of energy derived from a gravitating movement of the cage.

3. The combination with a gravitating self dumping rotary dump cage, of means operable as a fly-wheel to retard the gravitating movement of the cage and to give off sufficient stored energy to drive the dump to its righted position.

4. In a rotary dump, a gravitating self dumping cage having a car track disposed off center therein, and a fly-wheel driven by the dump, as and for the purposes described.

5. In a rotary unbalanced self dumping cage having a car track therein, trunnion wheels on which the cage rides and fly-wheels driven by the trunnion wheels and capable of storing sufficient energy from a gravity movement of the cage to right the cage.

6. In a rotary dump, a cage having a car track therein disposed to unbalance it, trunnion wheels on which the cage rides with frictional engagement only as it rotates, and fly-wheels positively driven by said trunnions and designed to right the cage by a frictional drive after the dumping operation.

7. In a rotary dump, a cage, car tracks therein disposed to bring the center of gravity of the cage with a loaded car therein above and to one side of the center of the cage, stop means to restrain the rotation of the dump, and fly-wheels driven by the dump and designed to store up enough energy during a gravitating movement of the

unbalanced cage to right it after the change in its center of gravity resulting from the dumping of the contents of the car.

8. In a rotary dump, an elongated cage having a car track disposed off center to unbalance it and a plurality of annular tire rails adapted to rotatably support said car track, a series of trunnions on which said tire rails turn, and a series of fly-wheels driven by the trunnions and distributed substantially uniformly lengthwise of the cage.

9. In a rotary dump, a cage mounted to rotate on roller supports, latch means to hold the cage in initial car receiving position, means to unbalance the dump with the loaded upright car on one side and with the empty inverted car on the other side, and a fly-wheel rotatable with the dump and adapted to oppose its inertia to the initial gravitating movement of the dump in either direction and to give out this stored energy on the reverse rotation of the dump to restore it to initial position.

10. In a rotary dump, a cage having annular tire rails on which it turns, roller supports for said rails, a pair of oppositely disposed stop lugs rigid on the sides of a tire rail, and a bifurcated pawl which straddles the rail tread and is movable to engage said lugs, as and for the purposes described.

11. In a rotary dump, an unbalanced rotary cage, a trunnion wheel on which said cage turns, and a pair of fly-wheels driven by said trunnion wheel.

12. In a rotary dump, an unbalanced rotary cage, a trunnion wheel on which said cage turns, a shaft for said trunnion wheel, bearings for shaft beyond which its ends overhang, and a pair of fly-wheels driven by said trunnion wheel and mounted on the overhanging ends of its shaft.

13. In combination, a pair of parallel rotary dumps, means to unbalance said dumps when loaded to cause them to gravitate in

opposite directions, means to right the dumps, and a common automatic frictional brake means interposed between the dumps.

14. In combination, a pair of parallel rotary dumps unbalanced to gravitate in opposite directions, means to right the dumps, a common brake means interposed between the dumps and comprising spring-pressed brake shoes having a rotating element of both dumps traveling between them, and projections on said element adapted to be frictionally engaged and stopped by said shoes.

15. In a rotary dump, a self dumping cage having means to unbalance it and cause it, when released, to rotate sufficiently to dump the contents of a loaded car therein, roller supports for the cage, means to support the car so that its center of gravity when inverted will be above the axis of the cage and disposed to unbalance the cage and cause it to rotate in a reverse direction to initial position, and a number of fly-wheels connected to the roller supports and adapted both to control the speed of the dumping movement and to restore the dump to initial position.

16. In an automatic rotary dump, in combination with a fly-wheel to control the speed of the dump's rotation, means to stop the dump in a predetermined position, and means to frictionally arrest the dump as it approaches said predetermined position.

17. In an automatic rotary dump which is unbalanced to rotate by gravity, roller supports for the dump, a fly-wheel to control the speed of the dump's rotation, means to stop the dump, and a frictional brake means acting by wedge and spring action on the dump to slow it up before said stop means arrests it.

In testimony whereof I affix my signature.
EDWIN J. BEST.
